(57) **CLAIM**

The ornamental design for a blood analysis system, as shown and described.

DESCRIPTION

FIG. 1 is a front right perspective view of the blood analysis system showing the new design;

FIG. 2 is a top view thereof;

FIG. 3 is a bottom view thereof;

FIG. 4 is a left side view thereof;

FIG. 5 is a right side view thereof;

FIG. 6 is a top view thereof;

FIG. 7 is a bottom view thereof;

FIG. 8 is a front right perspective view of the design in an open position; and,

FIG. 9 is an exploded top view thereof showing the upper and lower clam-shell portions of the design separated. The broken lines connecting the centers of the separated upper and lower clam-shell components are included to show the order of assembly.

The broken lines in the drawing views are included for the purpose of illustrating portions of the blood analysis system that form no part of the claimed design.
